UNITED STATES PATENT OFFICE.

JOHN M. WHITALL, OF PHILADELPHIA, PENNSYLVANIA, ASSIGNOR TO HIMSELF, CHARLES ALBERT TATUM AND FRANCIS M. UNDERHILL, OF NEW YORK, N. Y., AND JOHN W. NICHOLSON, OF MOORESTOWN, NEW JERSEY.

DESIGN FOR A BOTTLE.

SPECIFICATION forming part of Design No. 28,182, dated January 18, 1898.

Application filed March 29, 1897. Serial No. 629,864. Term of patent 14 years.

To all whom it may concern:

Be it known that I, JOHN M. WHITALL, a citizen of the United States, residing in Philadelphia, Pennsylvania, have invented a certain new and original Design for a Bottle, of which the following is a specification.

My design for a bottle is fully illustrated in the accompanying drawings, in which—
Figure 1 is a rear view of the bottle. Fig. 10 2 is a front view. Fig. 3 is a side view. Fig. 4 is a section on the line 4 4, Fig. 1; and Fig. 5 is an inverted plan or bottom view.

The essential feature of the design is the bottle oval in cross-section with one flat face 15 and having a bead at the bottom.

The back a and sides a' of the bottle are curved, as shown in Fig. 4, while the front a^2 is flat, being in the form of an elongated panel, as illustrated in Fig. 2.

20 At the bottom of the bottle is a bead b ,

which is offset inwardly in respect to the body of the bottle, and this bead is interrupted at the flat side a of the bottle, as shown in Fig. 2.

The bottle is rounded at $c c$, where the body joins the bead, and the straight sides of the 25 body terminate at the top in curves d , which join the sloping shoulders f , and the latter join the curves g at the base of the neck, which has the shape shown.

I claim—

30 The design for a bottle as herein described and as shown in the accompanying drawings.

In testimony whereof I have signed my name to this specification in the presence of two subscribing witnesses.

JOHN M. WHITALL.
